CLAIM

The ornamental design for a display screen with transitional graphical user interface, as shown and described.

DESCRIPTION

This patent or application file contains at least one drawing executed in color. Copies of this patent or patent application publication with color drawings will be provided by the U.S. Patent and Trademark Office upon request and payment of the necessary fee.

FIG. 1 is a perspective view of a display screen with transitional graphical user interface showing a first image in a sequence of a first embodiment of our new design;

FIG. 2 is a front view of the first image;

FIG. 3 is a second image thereof;

FIG. 4 is a third image thereof;

FIG. 5 is a perspective view of a first image in a sequence of a second embodiment of our new design;

FIG. 6 is a front view of the first image;

FIG. 7 is a second image thereof; and,

FIG. 8 is a third image thereof.

The white color background shown on the watch face in FIGS. 1-8 does not form part of the claimed design. The white color fill shown within the circular slider element in FIGS. 1-8 does not form part of the claimed design. The white color fill shown within the arcuate slider in FIGS. 1-2 and 5-6 does not form part of the claimed design.

The broken lines showing an electronic device and portions of the graphical user interface form no part of the claimed design.

The appearance of the transitional images sequentially transitions between the views of FIGS. 2-4 and FIGS. 6-8. The process or period in which an image transitions to another forms no part of the claimed design.
